United States Patent

Des. 237,287
Patented Oct. 21, 1975

237,287

TOY MOBILE

Ralph W. Crawford, East Aurora, N.Y., assignor to
The Quaker Oats Company, Chicago, Ill.

Filed Dec. 5, 1973. Ser. No. 421,774

Term of patent 14 years

Int. Cl. D21—01

U.S. Cl. D34—15 F

FIG. 1

FIG. 3

FIG. 4

FIG. 1 is a front perspective view of a toy mobile showing my new design;

FIG. 2 is a top plan view thereof shown on an enlarged scale;

FIG. 3 is a rear elevational view thereof with the vertical member broken off for purposes of clarity; and

FIG. 4 is a bottom plan view thereof with the horizontal member broken off for purposes of clarity.

I claim:

The ornamental design for a toy mobile, substantially as shown and described.
